UNITED STATES PATENT OFFICE

ANTHONY L. VISSAT, OF JEANNETTE, PENNSYLVANIA

RAILWAY-CROSSOVER FROG CONSTRUCTION

Application filed December 24, 1927. Serial No. 242,453.

One of the objects which I have in view is the provision of a new and improved railway cross-over frog structure which, although advantageously applicable for general rail-way use, is particularly designed for light railways, such as in mines, quarries and industrial plants.

In general, my improved cross-over frog structure comprises a fixed portion including the converging rail ends of the tracks and a movable portion including the frog point which may be positioned in registration with either of the rail ends.

The construction and arrangement of the elements of the cross-over frog structure are also included in the subject matter of my present invention.

One novel and important feature of my present invention is the use of sections of railway rails, such as lengths cut from old rails which may be repressed or reformed if necessary, as for fish-plates, limiting-bars and the like.

Other novel features of construction and arrangement of parts will appear from the following description.

In the accompanying drawings, wherein I have illustrated the best embodiment of the principles of my invention now known to me, Fig. 1 is a plan view of a movable frog structure, the frog point being thrown in the one direction; Fig. 2 is a similar but incomplete view, the frog point being thrown in the other direction; Fig. 3 is a side elevation of the structure shown in Fig. 2; Fig. 4 is an enlarged section taken along the line 4—4 in Fig. 1; Fig. 5 is an enlarged section taken along the line 5—5 in Fig. 1; Fig. 6 is an enlarged perspective showing a different point extremity than that shown in Fig. 4; Fig. 7 is a plan view showing another form of the same; Fig. 8 is a plan view of the base plate of the frog; Fig. 9 is a plan of a modified form of frog point; Fig. 10 is a view partially in end elevation and partially in cross-section showing a modified form of control means; Fig. 11 is a broken plan view showing my improved rail joint used in connection with a pair of stationary rails; Fig. 12 is a sectional view taken along the line 12—12 in

Fig. 11, and Fig. 13 is a side view showing the means for preventing the movable frog member from tipping.

Referring to the drawings, 1 represents the cross-ties upon which the movable frog structure and the fixed rail ends are supported. 2 represents the outer, uninterrupted rail of one track whose inner rail is represented by the rail ends 3a and 3b. 4 represents the outer, uninterrupted rail of the other and intersecting track whose inner rail is represented by the fixed rail ends 5a and 5b.

6 represents tie plates which may be interposed between the rails and the ties in the usual manner.

7 represents the base plate of the frog structure, substantially of the contour shown, and provided with spike-holes 8.

The converging extremities of the rail ends 3a and 5a extend onto and are supported on the base plate, and 9 represents a spaced block, which may be a casting of proper shape to fit between the extremities of the rail ends. 10 represents outer supporting members for the rail ends, the same being preferably formed of lengths of used rails, having their inner sides cut away, as by planing, so that the ball of the members 10 fit snugly against the ball of the rail ends, with the tread of the members 10 preferably at a somewhat higher level than the treads of the rail ends. The members 10 are spiked down through the base plate to the cross ties.

Stay bolts 11 extend through the members 10, the rail ends 3a and 5a and the spacer block 9.

The portions of the members 10 which extend inwardly past the rail ends are bent outwardly to diverge, thus forming opposed limiting bars for the frog point.

The frog point is formed of two converging "legs" 12 and 13 which are lengths of rails whose converging ends are arranged to form a "point" of the usual width as the cross-section area of the track rails. Thus in Fig. 4 the inner sides of the two leg rails are cut away so that the legs fit and are bolted as at 14 or otherwise fastened together. In Figs. 6 and 7 different methods are shown of cut-

ting down the rails to form the point. A triangular or filler block 15 is bolted or otherwise secured between the converging ends of the legs 12 and 13. When the frog is thrown in either direction, the side of the point bears against the inner side of one of the limiting members 10, thus causing the thrust to be assumed by the limiting member and holding the frog in proper alignment.

10 The ends of the treads of the members 10 are downwardly beveled, so that the passing wheels mount the treads of the members 10 and are carried over the joint between the rail end and frog without jolting or hammering.

15 One of the legs of the frog point is flexibly connected to one of the opposing rail ends, as for instance the leg 12 and the rail end 3b. I show a novel form for such connection. 20 Thus the outer side of the rail end 3b has clamped against it the member 16, the same being preferably a length of rail cut away on the inside so that its ball fits snugly up against the ball of the rail end 3b. The member is 25 straight and extends inwardly past the extremity of the rail end 3b so that when the frog point is in the position shown in Fig. 1, the outer end of the leg 12 bears laterally against the member 16, the ball of the rail fitting against the ball of the member. The 30 inner side of the rail end 3b has fitted against it the fish-plate 17 whose end portion which extends inwardly past the rail end 3b is curved toward the rail 2 so that when the frog 35 point is shifted into the position shown in Fig. 2, the leg 12 is supported laterally by the fish-plate. The fish-plate 17 and the member 16 are spiked to the ties and bolted to the rail 3b.

40 It is thus evident that the outer end of the leg 12 is flexibly connected to the rail end 3b and upon this connection the frog point moves as an axis.

45 The tread of the member 16 is slightly higher than the tread of the rail end 3b and of the leg 12 and the ends of the tread of the member 16 are beveled downwardly so that the wheels when passing over the joint between the rail end and the leg travel on the member 16 thus avoiding jolting and hammering.

50 It is evident that the frog point is flexibly connected to the rail end 3b so that it may be shifted so that it will register with either of the rail ends 3a or 5a, being alined in position by one of the limiting bars 10 which will assume the thrusts.

55 The leg 12 may be of any desired length but the leg 13 is preferably short enough to be slidably supported by the base plate 7.

60 18 is a member also preferably comprising a length of rail which is mounted against the outer side of the rail end 5b and extends inwardly beyond the latter to form a limiting member to properly aline the outer end of the

leg 13 with the rail end 5b when the frog point is shifted into the position shown in Fig. 2. This member is formed so that its ball will fit snugly up against the balls of the rail end 5b and of the leg 13 and its tread is slightly higher than their treads and is beveled downwardly at the end, thus forming an elevated bridge which will carry the wheels over the joint without jolting or hammering.

75 The adjacent end faces of the rail end 5b and of the leg 13 are inclined as shown so as to move readily into and out of registration without binding. Likewise the adjacent ends of the filler block 15 and of the member 18 are in parallel planes for a similar purpose.

80 The base plate 7 is provided with a longitudinally slotted opening 19 under the path of the leg 13 to provide for the downward escape of dirt or other obstructions which might tend to clog movement of the frog point.

85 20 is a central bar disposed transversely and in sliding contact with the underside of the base plate 7. 21 is a saddle resting on the bar 20 which extends up through a transversely slotted hole 22 in the base plate 7 and is clamped about the bases of the legs 12 and 13 where they converge. The legs are secured in the saddle and the saddle is secured to the bar 20 by the bolts 23. The bases of the limiting members 10 are cut out as at 24 for clearance for the saddle. One end of the bar 20 is connected as by a link 25 to the switch operating mechanism. The other end may be connected to the spring device 27 which normally holds the frog point in and returns it to the position shown in Fig. 2.

90 In Fig. 10 I show another form of operative means, the converging ends of the legs 12 and 13 being clamped between the angular ends 28 of the bars 29 which slide upon the upper surface of the base plate 7 being disposed transversely of said base plate and extending through the openings 24 in the limiting bars 10. The outer ends of the bars 29 are bent down and bolted to the bar 20 sliding beneath the plate 7, being held in place by the loop brackets 30 attached to the under side of said plate.

95 In Fig. 9 I show a modification of the frog point which is applicable to light railways, the leg 13 being flexibly connected by the oppositely hinged section 13a to the rail end 5b. When the frog point is shifted to aline the leg 13 with the rail ends 3a and 5b, the section 13a is alined with the leg 12 and the rail end 5b. When the frog point is shifted into the position shown in Fig. 1 to connect the rail ends 3a and 3b by the leg 12, the flexibility of the hinged intermediate member 13a permits the leg 13 to move out of alinement with the rail end 5b.

100 In Figs. 11 and 12 I show my improved

bridge joint applied to the connection of rails in fixed relation, the aligned rails being indicated at 31 and 32, the fish-plate which crosses the joint of the rails at one side being indicated at 33 and the rail-section member which crosses the joint at the other side of the rails being indicated at 34. The plate 33 and the member are spiked to the ties 1 and are clamped in place by the bolts 35 which extend through them and the webs of the two rails. The tread of the member 34 is above the level of the tread of the rails 31 and 32 and the ends of said elevated tread are beveled downwardly. It is thus seen that the member 34 functions not only as a fish-plate but also as a bridge to carry the wheels across the joint without the usual jolting and hammering which now results in discomfort to passengers, damage to rolling equipment and the smashing down of the ends of the rails.

In some cases there is a tendency toward upward tipping of the frog point or movable frog member at its point of registration with the fixed rail end due to the weight of traffic moving onto the other end of the rail member of the movable frog. This I prevent by providing said last named rail end with means to prevent its depression under traffic. Thus I have shown the leg 13 provided with a bar 36 bolted to the outer side of the leg 13 and protruding past the end thereof and arranged to ride up on the base of the rail end 5b and bear downwardly thereon to support the end of the leg 13 against depression. Thus the protruding end of the bar 36 may be notched out to ride up on a block 37 which may be secured as by welding to the base of the rail end 5b, as shown in detail in Fig. 13.

There are decided advantages in the use of lengths or sections of old rails for the purpose above described. One advantage is of course the cheapness and availability of the material. Another is that the ball and tread of the members so formed carry the wheels over but out of contact with the treads of the rail ends at flexible, interrupted or permanent joints. The old rails may, if necessary, be re-formed or repressed to obtain the necessary tread elevation and their abutting sides may be planed or otherwise cut away to enable the member to fit up snugly against the side of the rails with the balls in close proximity or contact. If old rails are not available or their use not desired the joint members and limiting members may be formed of new material into similar shape.

My improved movable frog structure is very simple and inexpensive and may be readily and quickly assembled from material and elements largely at hand. The use of sections cut from old rails enables me to employ material which would otherwise be sold as scrap.

I claim—

1. In a railway cross-over frog structure, the combination with a pair of converging rail ends, of a frog point comprised of converging leg-rails and arranged to be moved into registration with either of said rail ends, and means for preventing the point from tipping upwardly when a wheel engages the outer end of one of said leg rails, said means comprising a bar secured to and extending past the end of the leg-rail and bearing down on the base of the track rail when said leg-rail and track rail are in registration. 70

2. In a railway cross-over frog structure, the combination of a bed-plate, and a movable frog structure slidable thereon and comprising rail portions which are arranged to be brought into position to complete the fixed rails of the track, and means for preventing longitudinal tipping of said rail portions under moving traffic, said means comprising a bar secured to and extending past the end of the rail portion and bearing downwardly on the base of the track rail when said rail portion and track rail are in registration. 80

Signed at Pittsburgh, Pennsylvania, this 15th day of December, 1927.
